Fig. 2

To all whom it may concern:

Be it known that I, Frank C. Hull, a citizen of the United States and a resident of Kent, in the county of Portage and State of Ohio, having invented a new, original, and ornamental Design for an Automobile Identification Plate or the like of which the following is a specification, reference being had to the accompanying drawings, forming a part hereof.

In the drawings, Fig. 1 is a front elevational view of an automobile identification plate or the like, showing my new design; Fig. 2 is a side elevational view taken from the right of Fig. 1.

The dominant features of my design reside in those portions of the drawings shown in full lines.

I claim:

The ornamental design for an automobile identification plate or the like, as shown and described.
